UNITED STATES PATENT OFFICE.

NORMAN STAFFORD, OF CANASTOTA, NEW YORK.

RAKE.

SPECIFICATION forming part of Letters Patent No. 597,919, dated January 25, 1898.

Application filed September 17, 1896. Serial No. 606,131. (No model.)

To all whom it may concern:

Be it known that I, NORMAN STAFFORD, of Canastota, in the county of Madison, in the State of New York, have invented new and useful Improvements in Rakes, of which the following, taken in connection with the accompanying drawings, is a full, clear, and exact description.

My invention relates to improvements in rakes, and has for its object the production of a device which is simple in construction, strong and durable in use, and secures the teeth to the axle without liability of undue rattling and wear of the parts; and to this end it consists, essentially, in the general construction and arrangement of the support for securing the teeth to the axle.

In describing this invention reference is had to the accompanying drawings, forming a part of this specification, in which like letters indicate corresponding parts in all the views.

Figure 1 is a top plan view, partly broken away, of the detached axle of a rake and a number of teeth operatively secured thereto by my improved tooth-support. Fig. 2 is a vertical section taken on line 2 2, Fig. 1. Fig. 3 is an isometric view, partly broken away, of my improved tooth-support; and Fig. 4 is a vertical section of an axle and my improved tooth-support shown as mounted upon the upper face of said axle.

A is an axle, B B a series of teeth, and C a support for securing the teeth in position. The axle A preferably consists of a strip or bar of angle-iron and suitable spindles a a, secured to the opposite extremities of said strip or bar, and the teeth B are preferably formed of spring-wire and are provided with attaching ends b, having laterally-projecting extremities b'. The tooth-support C is usually formed of substantially the same length as the axle for securing all of the teeth thereto and consists of a substantially L-shaped angle-bar. It is obvious, however, that said support may be formed of considerably less length than the axle A, and that a number of the supports may be arranged end to end. The side c of the support C is preferably engaged with the lower face of the axle, and the side c' projects downwardly from the rear or inner edge of said side c. My improved tooth-support is not, however, necessarily ar-

ranged beneath the axle, and at Fig. 4 I have shown an axle A¹⁰ and a tooth-support C¹⁰, 55 arranged above said axle.

The outer or front portion of the lengthwise side c of the support C is preferably formed with a downturned extension c², a depressed forward extension c³, and an upward extension c⁴, forming a hook-shaped extension having a lengthwise groove or seat c⁵, which receives the laterally-extending extremities b' of the teeth B. The support C is formed with a series of slots c⁶, which extend through both faces of said support from the outer or lower portion of its side c' to the outer or front portion of its side c, where they terminate in the lengthwise groove c⁵ of the aforesaid hook-shaped extension. The slots c⁶ receive the 70 attaching ends of the teeth B and permit up-and-down movement thereof, and, as best seen at Fig. 2, the faces c⁷ at the lower ends of said slots limit the downward movement of the teeth B.

My improved tooth-support may be economically manufactured of rolled bars or sheet metal, is easily secured in position, is not liable to become unduly worn, and firmly and effectively supports and guides the teeth without liability of undue rattling and wear of the parts.

The operation and construction of my invention will now be readily understood upon reference to the foregoing description and the 85 accompanying drawings.

Having thus fully described my invention, what I claim as new, and desire to secure by Letters Patent, is—

As a new article of manufacture the herein-described tooth-support, the same consisting of an angle-bar having slots extending part way across and through both faces of said bar and a lengthwise recess or groove intersected by the aforesaid slots serving as a seat for the 95 teeth, substantially as and for the purpose described.

In testimony whereof I have hereunto signed my name, in the presence of two attesting witnesses, at Canastota, in the county of Madison, in the State of New York, this 12th day of September, 1896.

NORMAN STAFFORD.

Witnesses:

E. C. MILBURN,
ROBERT ROANTREE.
